(57) **CLAIM**

The ornamental design for optical component connection module, as shown and described.

DESCRIPTION

FIG. 1 is a top view of an optical component connection module;

FIG. 2 is a bottom view of the optical component connection module;

FIG. 3 is a first side view of the optical component connection module;

FIG. 4 is a second side view of the optical component connection module;

FIG. 5 is a front view of the optical component connection module;

FIG. 6 is a back view of the optical component connection module; and,

FIG. 7 is a top perspective view of the optical component connection module.
